[57] CLAIM

The ornamental design for a leaked water collection pan for an evaporative cooler, as shown and described.

DESCRIPTION

FIG. 1 is a perspective view of a leaked water collection pan for an evaporative cooler showing my new design;

FIG. 2 is a side elevational view thereof;

FIG. 3 is a top plan view thereof;

FIG. 4 is a side elevational view thereof, said side being opposite to that side shown in FIG. 2;

FIG. 5 is an end elevational view thereof, the other end elevational view being identical; and,

FIG. 6 is a bottom plan view thereof.

FIG. 1

FIG. 2

FIG. 3

FIG. 4

FIG. 5

FIG. 6
